UNITED STATES PATENT OFFICE.

HERMAN K. ANSINGH, OF TORONTO, ONTARIO, CANADA, ASSIGNOR TO WESTINGHOUSE ELECTRIC & MANUFACTURING COMPANY, A CORPORATION OF PENNSYLVANIA.

SWITCH MECHANISM.

Application filed October 6, 1922. Serial No. 592,767.

My invention relates to switch mechanism and particularly to disconnecting switch mechanism used in connection with circuit breakers of the truck-panel type, such, for instance, as the circuit breaker mechanism illustrated in my copending application Serial No. 592,766, filed October 6, 1922.

One object of my invention is to provide a disconnecting switch for a truck-type circuit breaker that is rigid in construction and which is self centering with respect to the stationary contact blades of the disconnecting switch, and which affords ample contact surface.

Another object of my invention is to provide a disconnecting switch wherein the switch jaws may be displaced a limited distance for the purpose of centering them with respect to the stationary contact blades, and wherein the conductors supporting the switch-jaw members are relatively flexible and have ample current-carrying capacity for insuring relatively low temperatures thereof under normal current conditions.

Another object of my invention is to provide stationary contact blades of U-shape which serve to support the bus bars connected thereto and which is simple in construction and easily assembled.

These and other objects, that will be made apparent throughout the further description of my invention, are attained by means of the apparatus hereinafter described, and illustrated in the accompanying drawings, wherein:

Figure 1 is an elevational view of the disconnecting switch mechanism;

Fig. 2 is a plan view of the stationary contact blades and a portion of the disconnecting switch-jaw members, and

Fig. 3 is a transverse section through the mechanism taken along the line III—III of Fig. 1, looking in the direction of the arrows.

Referring to the drawings, the apparatus includes an insulating tubular bushing 4 having clamp members 5 secured to the central portion thereof for the purpose of attaching the bushing to the rear face of a truck carrying the circuit breaker. The clamp member is provided with slots 6 for receiving bolts provided on the truck for securing the bushing thereto.

The end of the bushing 4 that projects

into the truck is provided with a cap member 7 having a rectangular opening 8 therein through which the terminal end of the switch-jaw member 9 extends. The switch-jaw member 9 comprises two pairs of metal conducting strips 11 and a spacing strap 12 that is disposed between them to constitute a laminated flexible shank portion 13 that extends entirely through the bushing. The straps 11 and 12 are clamped together at the terminal end of the shank by means of bolts 14 in the cap member 7. Bolts 14 constitute the primary support for the members 9.

The strap 12 terminates at the rear face of the cap member 7, and a space 15 is provided between the projecting ends of the straps 11 for receiving a terminal of the circuit breaker, which is secured to the straps by means of a bolt that extends through the perforations 16 in the straps 11.

The end of the bushing 4 that projects from the circuit breaker truck when assembled thereon is provided with a cap member 17 having a rectangular opening 18 therein of sufficient depth to permit of limited vertical movement of the shank member 13 with respect to the bushing. The projecting ends of the outermost straps 11 are bent outwardly at right angles to the shank member 13 and then in a direction parallel to the axis of the shank in such manner as to offset the ends of the outermost straps 11 with respect to the inner straps, as indicated in Fig. 1. The ends are provided with integral reentrant contact portions 19 that are adapted to yieldingly engage opposite sides of a pair of stationary contact blades that are secured to the stationary housing of the circuit breaker mechanism.

A bolt 21 extends through all of the straps constituting the contact jaw for the purpose of limiting their separation. Because of the laminated construction of the shank 13, the entire contact-jaw structure is relatively flexible and, consequently, the contact-jaw members automatically center themselves with respect to the stationary contact blades when moved into engagement therewith, regardless of any irregularities in the rails on which the truck operates which might throw the contact jaws out of alinement with the contact blades.

The central strap 12 serves to reinforce the

contact-jaw structure and to provide extra conducting material. Ample current-carrying capacity is, therefore, provided and any tendency for overheating of the shank within the bushing is prevented, thus insuring greater durability of the entire structure.

The contact blades comprise a metal strap 22 of U-shape that is secured to an insulating bushing 23 by means of a clamp structure 24 and clips 25 that are secured to the contact blade strap 22 by means of bolts 26. Two integral blades 27 are retained in spaced relation by means of spacing tubes 28, and the bus bars for supplying current to the contact blades are bolted to the outer surface of the blades by means of bolts 29 that extend through the bus bars, blades and spacing tubes.

The blades, therefore, constitute a rigid support for the bus bars which may extend transversely of the circuit-breaker housing in the usual manner. The construction is rigid and compact and the blades are rigidly secured in position. When the disconnecting switch is in operative engagement with the contact blades, the members of the apparatus occupy the position indicated in Fig. 1.

While I have illustrated and described but one embodiment of my invention, it will be apparent to those skilled in the art that various changes, modifications, additions, substitutions and omissions may be made in the apparatus illustrated without departing

from the spirit and scope of my invention, as set forth in the appended claims.

35

I claim as my invention:

1. A switch-jaw member comprising five relatively long and flexible conducting strips secured together at one end and constituting a relatively flexible laminated conducting member, the outermost pairs of strips being offset with respect to one another and provided with reentrant contact surfaces for engaging opposite sides of a pair of contact-blade members.

40 2. The combination with a pair of spaced bus bars and a supporting member, of a metal conducting strip of U-shape secured to the bus bars and having end portions extending transversely of, and beyond, the bus bars and constituting contact blades, and means for securing the strip to the supporting member.

45 3. The combination with a pair of spaced bus bars and a supporting member, of a metal conducting strip of U-shape having end portions extending transversely of, and beyond, the bus bars and constituting contact blades, tubular spacing means between blades, and bolts extending through the bus bars, blades and spacing means for securing the bus bars to the strip.

50 In testimony whereof, I have hereunto subscribed my name this 25th day of September, 1922.

HERMAN K. ANSINGH.
